UNITED STATES PATENT OFFICE.

ROBERT O. BOARDMAN, OF GRAND RAPIDS, MICHIGAN, ASSIGNOR TO MERTENTHALER LINOTYPE COMPANY, A CORPORATION OF NEW YORK.

TYPOGRAPHICAL MACHINE.

1,076,187.

Specification of Letters Patent.

Patented Oct. 21, 1913.

Application filed May 3, 1912. Serial No. 694,867.

To all whom it may concern:

Be it known that I, ROBERT O. BOARDMAN, a citizen of the United States, and a resident of Grand Rapids, county of Kent, and State 5 of Michigan, have invented a new and useful Improvement in Typographical Machines, of which the following is a specification.

My invention relates to typographical machines, such as linotype machines of the general organization set forth in Letters Patent 10 of the United States to O. Mergenthaler, No. 436,532, wherein circulating matrices are released from a magazine in the order in which their characters are to appear in 15 print, and then assembled in line together with spacers, the composed line transferred to the face of a mold, the mold filled with molten metal to form a slug or linotype 20 against the matrices which produce the type characters thereon, and the matrices thereafter elevated and returned through a distributing mechanism to the magazine from which they started.

25 More particularly, it relates to the distributing mechanism and to the means employed for presenting the type or matrices thereto.

In the ordinary commercial linotype machine, the distributing mechanism comprises 30 rotating screws which convey the matrices along a rail or bar, from which they drop at the proper points into the channels of the magazine from which they were originally 35 released. The matrices are presented one at a time to the action of these screws by a vertically reciprocating member or lifting finger, and it sometimes happens that a matrix will not be engaged properly by the finger 40 or that it is incorrectly presented thereby to the screws. Thus, for instance, it may fail to enter between the screw threads, or become jammed between the thread and the side plates, or slip over the top of the finger, 45 or similar accidents may occur to prevent its proper delivery. Such abnormal action ordinarily results in the arrest of the lifting finger or subjects it to undue resistance, and therefore the parts are constructed to yield 50 so as to obviate breakage or injury thereto or to the matrix. It sometimes happens that such yielding means are not sufficient to prevent the matrices from being bent or mutilated, and I therefore provide connections 55 whereby the action of the distributing mech-

anism is instantly arrested in the event that a matrix is thus improperly presented. To this end I avail myself of the relative movement between the yieldingly connected parts which occurs in the event of undue resistance, and specifically I prefer to connect the arresting means to the device which actuates the lifting finger.

In the accompanying drawing, I have shown my improvement by way of example 60 and in preferred form, and as applied to the specific kind of mechanism already mentioned, but obviously many changes and variations may be made therein, and similarly it may be used in connection with other 70 forms of typographical machines, such as typesetters, typecasters and the like, without departure from its spirit; and generally speaking, I desire it to be understood that I do not limit myself to any specific form or 75 embodiment except in so far as such limitations are specified in the claims.

Referring to the drawing: Figure 1 is a rear view of one end of the distributing mechanism, showing its actuating means and 80 disengaging mechanism therefor; Fig. 2 is a rear view of the other end of the distributing mechanism, showing the presenting means and my invention applied thereto, and illustrating the parts in normal relation; and Fig. 3 is a similar view, the parts 85 being in a different relation.

Referring to the drawing, the distributing mechanism is or may be of the ordinary form, and comprises the conveying screws 90 A, the rail or bar A¹, the side plates or rails A² of the distributor box, and the vertically reciprocating lift or finger B, whereby the matrices X are transferred one at a time to the screws.

The screws A are rotated in the usual way (see Fig. 1) by gearing comprising the two friction-clutch members R and Q, the latter being movable to make or break the friction connection, and formed with the lateral cam surface Q¹. Mounted in proximity to the clutch is the rock shaft O carrying the arm P and the pin P¹ to engage the cam Q¹, and also carrying the detent N. A spring O¹ (shown in dotted lines) normally tends to 100 move the pin P¹ into the path of the cam Q¹, which tendency of the spring is resisted and controlled by the engagement with the detent N of the arm or pawl M on the customary stop bar L. This bar is longitudi- 105

nally movable to disengage the arm M from the detent N, thereby permitting the spring O¹ to project the pin P¹ into the path of the rotating cam Q¹, the result of which action 5 is to disengage the clutch member Q from the clutch member R and to arrest the action of the distributing mechanism. This well-known form of stop mechanism has been described simply by way of example, and in 10 itself constitutes no part of my invention.

Referring more particularly to the matrix presenting means, as disclosed in Figs. 2 and 3, the lifting finger B is connected to the reciprocating arm C, which receives its motion from the arm D, the latter being held by the spring D¹ in operative relation to the cam E at the end of one of the screws A. The two arms C and D are independently mounted on the same pivotal axis, as at C¹, 20 but are so connected as normally to move together, to this end a spring F being interposed between the operating arm D and the rigid extension C² of the arm C. As usual, the spring F is mounted in a socket F¹ connected to the arm D. In the ordinary operation of the parts, the strength of the spring F is sufficient to reciprocate the arm C and finger B, and to introduce the matrix X between the threads of the screws A, as shown 25 in Fig. 2. However, in the event of undue resistance, the spring F is compressed and this permits relative movement between the two arms C and D, this yielding connection being provided to prevent breakage or injury to the parts or to the matrix.

All of the features so far described are or may be substantially the same as those known in the art, and in themselves constitute no part of my present invention.

40 Notwithstanding the yielding connection already described, it may happen that a matrix in engagement with a screw will become lodged or jammed in such manner as to prevent its advance thereby, which abnormal condition results in the bending or breaking of a matrix or other derangement. In order to prevent these and similar accidents, I provide additional means whereby the action of the distributing mechanism is 45 promptly arrested, in the event that a matrix is improperly presented thereto, or if for any reason the operation of the lifting finger be arrested or if it be subjected to undue resistance. To this end I preferably 50 rely upon the relative movement between the two arms C and D, which results from the arrest or retardation of the former in the manner previously described. I therefore pivotally mount a lever G upon an extension C³ of the arm C and connect its upper end by a link H to the upper end of the arm D. The lower end of the lever G is connected 55 to a piece J slidably mounted upon the arm C³ by the pin and slot K. The end of the 60 slide J is located in proximity and operative

relation to the stop bar L, or to an extension L¹ thereof, the longitudinal movement of the bar L¹ arresting the distributing mechanism in the manner previously described.

In ordinary operation, and as shown in 70 Fig. 2, the matrix X is delivered by the reciprocating finger B between the threads of the screw A. When the parts are thus normally operating, the relative positions of the link H, lever G, and slide J, to the supporting arm C and to the stop bar L, are not affected or altered. If, however, the matrix be improperly presented, as for instance if a matrix X¹ be delivered into contact with one of the screw threads, and at the same time 80 remains in engagement with the side plates or rails A², as shown in Fig. 3, the upward movement of the finger B is arrested. The screw A continues to rotate, and consequently the cam E continues to act upon the arm D, and the latter moves outwardly with reference to the arm C about its axis C¹, which relative or yielding movement is permitted by the compression of the spring F. In these circumstances, the link H turns the 85 lever G about its pivot, and thereby the slide J is moved to contact with and shift the stop bar L, which causes the immediate arrest of the distributing mechanism in the manner previously described. The particular instance mentioned has been noted simply by 90 way of illustration, as obviously any displacement or abnormal action, which arrests or tends to arrest the upward movement of the finger B, will similarly act through the 95 connections described to arrest the distributing mechanism.

As previously noted, I have shown my invention in preferred form and by way of example, but obviously many changes and variations therein will suggest themselves to those skilled in the art and still be comprised within its scope.

Having thus described my invention, its construction and mode of operation, what I 110 claim and desire to secure by Letters Patent of the United States, is as follows:

1. In a typographical machine, the combination of distributing mechanism, means for presenting type or matrices thereto, and devices controlled by said presenting means to arrest the action of the distributing mechanism in the event that a type or matrix is 115 improperly presented thereto.

2. In a typographical machine, the combination of distributing mechanism, lifting means to present the type or matrices thereto, and devices controlled by said lifting means to arrest the action of the distributing mechanism in the event that a matrix is 120 improperly presented thereto by the lifting means.

3. In a typographical machine, the combination of distributing mechanism comprising a conveying screw, means for presenting 130

the type or matrices to the screw, and devices controlled by said presenting means to arrest the operation of the distributing mechanism in the event that a matrix is improperly presented thereto.

4. In a typographical machine, the combination of distributing mechanism comprising a conveying screw, a lifting finger to present the type or matrices to the screw, and devices controlled by said lifting finger to arrest the action of the distributing mechanism in the event that a matrix is improperly presented thereto by the lifting finger.

5. In a typographical machine, the combination of distributing mechanism, a member to present the type or matrices thereto, means for reciprocating the said member, and devices controlled by the said reciprocating means to arrest the distributing mechanism in the event that a type or matrix is improperly presented by the member thereto.

6. In a typographical machine, the combination of distributing mechanism, a yieldingly mounted member to present the type or matrices thereto, and devices to arrest the movement of the distributing mechanism in the event of undue resistance to the presenting member.

7. In a typographical machine, the combination of distributing mechanism, a member to present the type or matrices thereto, means for actuating the said member yieldingly connected thereto, and devices to arrest the action of the distributing mechanism in the event of undue resistance to the presenting member.

8. In a typographical machine, the combination of distributing mechanism, means for presenting type or matrices thereto, and devices controlled by said presenting means to arrest the action of the distributing mechanism in the event of the improper presentation of a type or matrix thereto, the said devices comprising a yielding member and suitable arresting connections.

40
45
nation of distributing mechanism, means for presenting type or matrices thereto, and devices controlled by said presenting means to arrest the action of the distributing mechanism in the event of the improper presentation of a type or matrix thereto, the said devices comprising a yielding member and suitable arresting connections.

45
50
55
9. In a typographical machine, the combination of distributing mechanism, means for presenting type or matrices thereto, and devices controlled by said presenting means to arrest the action of the distributing mechanism in the event of the abnormal operation of the presenting means.

60
65
10. In a typographical machine, the combination of distributing mechanism, means for presenting type or matrices thereto, and devices controlled by said presenting means to arrest the action of the distributing mechanism when the action of the presenting means is arrested.

65
70
11. In a typographical machine, the combination of distributing mechanism, means for presenting type or matrices thereto, said means comprising connected parts adapted normally to move in unison therewith but capable of moving relatively thereto, and devices actuated by the said relative movement for arresting the action of the distributing mechanism.

In testimony whereof I hereunto set my hand this 29th day of April, 1912, in the presence of two attesting witnesses.

ROBERT O. BOARDMAN.
